THREAD HANDLING DEVICE

Richard W. Stanley, Drexel Hill, Pa., assignor
to American Viscose Corporation, Wilmington,
Del., a corporation of Delaware

Application March 27, 1945, Serial No. 585,127

18 Claims. (Cl. 28—71.7)

1

This invention relates to thread-handling devices and particularly to devices which serve the purpose of drawing the thread from one stage of operation and delivering it to another. The device of the invention is interchangeable from a simple thread-feeding rotor of the type frequently referred to as a godet to the form of a thread-advancing reel in which the strand is received at one end of the rotor and is advanced in a helical path to the other end of the rotor.

It is well known that the action of a godet or simple rotor is merely to wrap the strand around it until the strand is led off to another device, and such wrapping occurs at one spot so that the turns tend to build up around one peripheral line of the rotor; unless a special lap-displacing guide is associated with the rotor so that each convolution of the strand is separated from the rotor and taken about the guide either through special hooks on the guide or with the guide canted with respect to the axis of the rotor. On the other hand, a thread-advancing reel automatically carries the strand in helical turns from the receiving end of the reel to the opposite end from which it generally is discharged. If the reel is free of obstructions adjacent the discharge end, it may be undesirable for such discharge to occur, since the strands may fall into a lower portion of a machine containing such reel where it may cause trouble with operation of the machine. At times it is desirable, therefore, to have a device which is selectively operable either as a simple thread-feeding or thread-collecting rotor or as a thread-advancing reel. For example, during the preliminary lacing up of a machine, it may be desirable to prevent the thread from going to a successive stage of the operating machine until the operator is certain that the extrusion or other preliminary stages are functioning well. During such time of preliminary observation, the operator may lead the thread to the interchangeable device of the present invention while operating it as a simple godet, so that the freshly extruded yarn is collected right at this scene of observation until such time as he is satisfied that the operation is successful and the thread is ready to be passed through the entire sequence of operation in the machine, whether this be a continuous machine in which the entire series of liquid treatments for finishing the thread and the drying treatment are performed, or merely a machine of the non-continuous type in which the coagulated thread, with or without stretching between pairs of devices of the present invention

2

operating at successively higher speeds, and, with or without preliminary washing are collected in a preliminary wet state. After the operator is satisfied with the extrusion or other operation, he puts the device of the present invention into operation as a thread-advancing reel, which discharges whatever has been wrapped upon the godet and advances following portions of the strand in a helical path thereabout, so that the operator can break off the preliminarily collected waste portion and advance the following portion of the strand through the subsequent stages of the machine. Such a procedure localizes the collection of waste where it is readily observable and separable from the standard product, whereas if the thread were allowed to pass through all stages of the machine to the final collecting device, such as a bobbin, twister or spinning pot, a subsequent separation is difficult, and it may be necessary to throw out a safe margin of good quality material in order to be sure that the preliminarily collected waste portion is entirely removed.

25 The device of the present invention, though described in connection with the artificial filament spinning art, is applicable to handling threads and strands in general, particularly where situations analogous to that just mentioned are involved. It is to be understood, however, that the devices of the present invention can be used in other ways to accomplish other purposes. It is thought that the advantages and objects of the invention will be apparent from the drawings and the description thereof hereinafter.

In the drawings, which are illustrative of the invention,

Figure 1 is a cross section of one embodiment of the invention;

40 Figure 2 is a section taken on the line II—II;
Figure 3 is a cross section of a modification;
Figure 4 is an elevation showing a mounting arrangement of the embodiment of Figure 3;

Figure 5 illustrates a modification of the embodiment of Figure 3; and

Figure 6 is a modified arrangement of the embodiment of Figure 5.

As shown in Figures 1 and 2, the device of the invention is mounted in a frame 2, a main bearing 3 being provided for receiving a central shaft 4 which carries a gear 5 by which the device may be driven. A sleeve 6 is carried rotatably upon the shaft 4. At opposite ends the sleeve 6 carries the discs 7 and 8 respectively which are keyed or otherwise secured for rotation with the sleeve.

The members 1 and 8 carry annular cams 9 and 10 respectively, so that their cam surfaces are parallel. A supporting block 10a is carried upon an eccentric portion 11 of the peripheral surface of the sleeve 6 and is rotatable with respect thereto. The block 10a contains a plurality of bores 12 within which plungers or pistons 13 are slidable. The plungers 13 carry rollers 14 at each end for following the respective cams 9 and 10, thereby to be reciprocated. There is secured to each plunger, such as by a nut 15, a supporting web 16 which carries fixed thereto one or more of the actuatable bar members 17 which extend into the spaces between the bars 18 of the other set which constitute the concentric reel. The concentric reel comprises an inner supporting flange 19 and an outer supporting web 20 which may be suitably secured as by bolts 21 to the inner flange 19, the bars 18 as shown being molded integrally with the web 20. Flexible sealing members 22 and 23 may be secured to the inside of the flanges 19 and 20 and to the opposite sides of the webs 16 to prevent the entrance of any liquids which may be applied to the strands on the periphery of the device from entering into the operating parts of the device. As shown, a suitable bearing, such as 25, is provided to support the web or flange 20 concentrically with respect to the axis of the main shaft 4. A labyrinthine seal 26 may be provided to prevent entry of any liquids into the bearing 25 and other operating portions of the device. A bearing and clutch block 27 is keyed or otherwise fixedly secured to an outer portion of the sleeve 6 concentric with the axis of the shaft 4. An arm 28 pivotally mounted with respect to the frame 2 at 29 is shown with a clutch portion 30 in engagement with the clutch face of the block 27. The engaging face of the member 30 has a plurality of spaced depressions 31, each consisting of a portion of a spherical surface arranged in an annular ring therein. Co-operating with the depressions 31 there are provided an annular ring of spaced recesses 32 receiving partially protruding balls 33 which are normally forced outwardly by springs 34 bearing against the bottom of the recesses. Screwed inset rings 35 have overhanging lips which prevent complete discharge of the balls 33 from the recesses. As shown, the clutch member 30 has a flexible sealing ring 36 which bears against the adjacent inwardly sloping face 37 of the web 20. The web 20 is arranged to overhang the member 30 and the outer surface of the clutch member 30 is sloped to a gradually decreasing diameter or neck at 38, so that any bunch of material discharged over the end of the device will fall along the surface of the clutch member 30 to the neck 38, where it will be suspended out of the way of operations.

As shown in Figure 1, the device is operating as a reel, since the spring 39 secured to the arm 28 and the frame 2 forces the clutch face of the member 30 into engagement with the complementary clutch face of the block 27 carried by the eccentric sleeve 6. By thus holding the eccentric sleeve stationary, the eccentric set of bars 17 are carried by their pistons 13 about the eccentric axis of the stationary sleeve 6, while the cams 9 and 10 are held stationary by the sleeve 6, so that actuation of the bars 17 is effected. This actuation is well known in the art and involves the movement of the bars 17 axially of the reel in the direction of advance of the thread during their intervals of protrusion from the main cage of bars 18. The cams 9 and 10 are so related

with respect to the eccentric as to accomplish advance of the thread during protrusion of the actuated bars from the fixed bars 18 and to return the bars 17 axially of the reel in the portion of the periphery thereof where they are in a receded position with respect to the fixed bars 18.

If it is desired to operate the device as a simple rotor, it is merely necessary for the operator to swing the arm 28 about the pivot 29 into the dotted line position shown in Figure 1, where the spring 39 will retain it by virtue of the fact that the line of the spring is offset from the pivot 29 in a direction opposite to that in which it forces the clutch 30 into engagement with the complementary clutch member of the device. In the dotted line position of the arm 28, the eccentric sleeve 6 is free to rotate with the shaft 4 and does so, so that both sets of bars are rotated bodily as a unit about the axis of the shaft 4 and there is no actuation of the bars 17 relative to the concentric set of bars 18 since there is no relative motion between the shaft 4 and the eccentric sleeve 6.

Devices of this type may be substituted for the other forms of thread-advancing devices, such as godets and associated lap-displacing guides, thread-advancing reels, and the like, in continuous or non-continuous artificial filament spinning machines, such as those which collect either a dry- or wet-ground package of filaments in a spinning bucket, on a bobbin, or on a twister, such as a cap or ring twister. When such devices are substituted for those heretofore used, it is advantageous to lace up the machine with the arm 28 swung out of the way, and as each device is laced up, and at the time the operator decides that he desires to proceed to the next device and lace it up, he can swing the arm 28 downwardly or upwardly as the case may be, depending upon the positional relationship of the pivot 29 to the device, and thereby automatically convert it into a thread-advancing device. The arms 28 with its associated clutch member 30 serve not only to give additional support to the outer end of the device and to convert the device into a thread-advancing reel, but also as mentioned above, to catch any wound mass of thread collected on the device immediately prior to its being put into operation as a reel. It is to be understood that the device is being rotated by means of the gear 5 and shaft 4 continuously even during the time required to change its operation from that of a simple rotor to that of a thread-advancing device.

Figures 3 and 4 show a modification in which the central shaft 4a has a bore through which a rod 40 extends and is freely slidable therein. The fixed reel members 18a carried by the web 20a are fixed for rotation with the shaft 4a and the flange 21a carries a sleeve 41 extending back to the frame 2a, a labyrinthine seal 42 being provided to permit relative rotation while preventing entrance of foreign material into the operating parts of the device. The sleeve 6a having the eccentric portion 11a for carrying the supporting block 10a is provided with an outwardly projecting flange 42a carrying an inwardly extending annular rim or sleeve 43. The bearing 3a carries slidably mounted thereon a clutch member 44, a key 45 serving to prevent relative rotation between the bearing 3a and the member 44. The clutch member 44 is provided with radial recesses 45 receiving springs 46 which press outwardly balls 47 co-operating with complementary depressions in the rim 43 of the eccentric sleeve 6a. The rim 43 has an annular groove 48 which has at

spaced points thereabout laterally extending branch grooves 49 so that in the position of the block 44 as shown, the eccentric 6a is freely rotatable with respect to the frame 3a and the clutch 44 but when the member 44 is forced in a direction to the left as viewed in Figure 3, the balls 47 engage the spaced grooves 49 on the inner periphery of the rim 43, thereby preventing relative rotation of the eccentric sleeve 6a with respect to the frame 3a and the clutch 44, unless such a high torque is applied to the sleeve 6a tending to rotate it that the outward force of the springs 46 against the balls 47 is overcome. Two or more rods 50 are secured symmetrically to the clutch member 44 and extend slidably through the frame 2a. The rods 50 are provided with transverse pins 51 which extend into slots 52 of levers 53 mounted on pivots 54. The other ends 10 of levers 53 carry similar slots 55 which co-operate with the transverse pin 56 or equivalent means on the rod 40. A spring 57 received in a recess of a frame part normally urges the rod 40 to the position shown in Figure 3.

The outer end of the rod 40 which protrudes from the axis of the device is adapted to be pressed inwardly by an arm 28a pivotally mounted at 29a and under the control of spring 39a similar to the arrangement of Figures 1 and 2. In the position of Figure 4, the rod 40 is pressed inwardly, which causes sliding of the clutch 44 so that the eccentric sleeve 6a is kept from rotation with respect to the frame 2a, thereby causing operation of the device as a thread-advancing reel. Merely by swinging the arm 28a out of the way, in a fashion similar to that shown in Figure 1, the rod 40 and clutch member 44 take the position shown in Figure 3, in which the eccentric sleeve 6a rotates with the shaft 4a and there is no actuation of the eccentric set of bars.

In the embodiment of Figure 5, an arrangement is shown similar to that in Figure 3, except that the arm 28 may be eliminated. In this embodiment, a rod 40a similar to rod 40 of Figure 3 mounted slidably and rotatably within the shaft 4a and extending outwardly from the reel, as in Figure 3, beyond the driving gear, is provided with a knob 60 at its outer end by which the operator can easily manipulate it. The other end of the rod is provided with a transverse pin 61 which fits within a cylindrical bore 62 of a stationary member 63. The rod 40a extends through a bore 64 of the member 63, so that it is slidably and rotatably mounted therein. A transverse slot or keyway 65 is formed adjacent a portion of the bore 64 and extends from the bottom of the bore 62. In the position shown in Figure 5, the pin 61 is prevented from entering the slot 65, whereas by simply turning the rod 40a at a 90° angle, the pin 61 will be aligned with the keyway 65 and the spring 66 will urge the rod with the pin 61 to the left into the keyway. The rod 40a is provided with a collar 67 rotatably mounted thereon (and restrained from axial motion by the fixed collars 67a and 67b) and carrying an outwardly projecting pin 68 for engaging slots 55a of the clutch-engaging and disengaging linkage of the type shown in Figure 3. Thus by simply turning the knob 60 to a direction at right angles to that shown in Figure 5, the spring 66 is allowed to come into play to disengage the clutch 44a, so that the device will operate as a simple rotor or godet, whereas the operator can again merely push the rod 40a inward and turn the knob 60 in order to make the device resume operation as a thread-advancing reel.

Whereas the rod 40a is shown in Figure 5 as extending through the shaft 4a, it may be arranged so that it extends through an adjacent portion of the supporting framework for the device as shown in Figure 6 where it is designated 40b. An additional linkage 69 pivoted at 70 and carrying the pin 71 serves to connect with the links 53 and the rods 50 carried by the clutch member 44 as shown in Figure 3.

While specific forms of mechanism have been shown for effecting thread-advancing actuation of their supporting members, such as sets of bars, it is to be understood that the invention can be applied to any form of reel comprising conventionally actuatable thread-supporting members, the invention herein being directed primarily to the arrangement and construction by which a thread-handling device can be converted selectively and alternately back and forth at will from a simple rotor to a thread-advancing reel, regardless of the specific construction of the actuating mechanism for the thread-supporting members.

It is to be understood that changes and variations may be made without departing from the spirit and scope of the invention as defined in the appended claims.

I claim:

1. A thread-handling device comprising two eccentrically disposed sets of bars, the bars of each set having their thread-supporting surfaces lying in a substantially cylindrical surface, a rotatable shaft, one set of bars being substantially concentrically secured to the shaft for rotation therewith, an eccentric rotatably mounted on the shaft, the other set of bars being rotatably mounted with respect to the eccentric, means secured to the eccentric for reciprocating the second set of bars during rotation of the bars relative to the eccentric, means for selectively imparting and preventing relative rotation between the eccentric and the bars whereby reversible interchange of operation of the device is effected between a thread-advancing condition and a non-advancing condition.

2. A thread-handling device comprising two eccentrically disposed sets of bars, the bars of each set having their thread-supporting surfaces lying in a substantially cylindrical surface, a rotatable shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during the rotation thereof relative to the eccentric, clutch means, and means for disengaging and engaging the clutch means with the eccentric for selectively imparting and permitting relative rotation between the eccentric and the bars whereby reversible interchange of operation of the device is effected between a thread-advancing condition and a non-advancing condition respectively.

3. A thread-handling device comprising two eccentrically disposed sets of thread-supporting bars, the bars of each set having their thread-supporting surfaces lying in a substantially cylindrical surface, a rotatable shaft, a supporting frame-work for the shaft, one set of bars being substantially concentrically secured to the shaft for rotation therewith, an eccentric rotatably mounted on the shaft, the other set of bars being rotatably mounted with respect to the eccentric, cam means secured to the eccentric for recipro-

cating the second set of bars during rotation thereof relative to the eccentric, a clutch member connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively.

4. A thread-handling device comprising two eccentrically disposed sets of thread-supporting bars, the bars of each set having their thread-supporting surfaces lying in a substantially cylindrical surface, a rotatable shaft, a supporting framework for the shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during rotation thereof relative to the eccentric, a clutch member connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively, said clutch member being carried by an arm pivotally connected to the framework at a point offset peripherally from the device and arranged to extend alongside the device to support the clutch member adjacent the outer end thereof during engagement thereof with the clutch means.

5. A thread-handling device comprising two eccentrically disposed sets of thread-supporting bars, the bars of each set having their thread-supporting surfaces lying in a substantially cylindrical surface, a rotatable shaft, a supporting framework for the shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during rotation thereof relative to the eccentric, a clutch member slidably mounted on a stationary element connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively.

6. A thread-handling device comprising two eccentrically disposed sets of thread-supporting bars, the bars of each set having their thread-supporting surfaces lying in a substantially cylindrical surface, a rotatable shaft, a supporting framework for the shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during

rotation thereof relative to the eccentric, a clutch member slidably mounted on a stationary element connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively, a reciprocable element connected to the clutch member for moving it into and out of engagement, spring means normally urging the element toward one extreme of its motion, and releasable means for holding the element toward the other limit of its motion in opposition to the spring means.

7. A thread-handling device comprising two eccentrically disposed sets of thread-supporting bars, the bars of each set having their thread-supporting surfaces lying in a substantially cylindrical surface, a hollow rotatable shaft, a supporting framework for the shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during rotation thereof relative to the eccentric, a clutch member slidably mounted on a stationary element connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively, a reciprocable rod extending through the shaft, projecting from the device and connected to the clutch member for moving it into and out of engagement, spring means normally urging the rod toward one extreme of its motion, and releasable means for holding the rod toward the other limit of its motion in opposition to the spring means.

8. A thread-handling device comprising two eccentrically disposed sets of thread-supporting bars, the bars of each set having their thread-supporting surfaces lying in a substantially cylindrical surface, a hollow rotatable shaft supported adjacent one end only, a supporting framework for the shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during rotation thereof relative to the eccentric, a clutch member slidably mounted on a stationary element connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively, a reciprocable rod extending through the shaft, projecting from the device and connected to the clutch member for moving it into and out of engagement, spring means normally urging the rod toward one ex-

treme of its motion, and releasable means for holding the rod toward the other limit of its motion in opposition to the spring means.

9. A thread-handling device comprising two eccentrically disposed sets of thread-supporting bars, the bars of each set having their thread-supporting surfaces lying in a substantially cylindrical surface, a rotatable shaft, a supporting framework for the shaft, one set of bars being substantially concentrically secured to the shaft for rotation therewith, an eccentric rotatably mounted on the shaft, the other set of bars being rotatably mounted with respect to the eccentric, cam means secured to the eccentric for reciprocating the second set of bars during rotation thereof relative to the eccentric, a clutch member connected to the framework, complementary clutch means connected to the eccentric, the clutch member being movable into and out of engagement with the clutch means for imparting and permitting relative rotation between the eccentric and the bars whereby reversible interchange of operation of the device is effected between a thread-advancing condition and a non-advancing condition respectively, said clutch member being carried by an arm pivotally connected to the framework at a point offset peripherally from the device and arranged to extend alongside the device to support the clutch member adjacent the outer end thereof during engagement thereof with the clutch means, said arm having a portion tapering to a smaller diameter away from the device.

10. A thread-handling device comprising a plurality of thread-carrying members forming a generally cylindrical periphery, the members having their thread-carrying portions extending generally lengthwise of the device, means for rotating the device, means for actuating the members for advancing a thread carried in a generally helical path thereabout lengthwise of the device, means for selectively putting the actuating means into and out of operation respectively, a frame member disposed adjacent one end of the device for supporting it, and a control member for the selective means comprising an arm carried by the frame member and movable to and from a position of engagement with the other end of the device to effect reversible interchange of operation of the device between a thread-advancing condition and a non-advancing condition respectively.

11. A thread-handling device comprising a plurality of thread-carrying members forming a generally cylindrical periphery, the members having their thread-carrying portions extending generally lengthwise of the device, means for rotating the device, means for actuating the members for advancing a thread carried in a generally helical path thereabout lengthwise of the device, means for selectively putting the actuating means into and out of operation respectively, a frame member disposed adjacent one end of the device for supporting it, and a control member for the selective means projecting generally axially through the device to the unsupported end thereof.

12. A thread-handling device comprising a plurality of thread-carrying members forming a generally cylindrical periphery, the members having their thread-carrying portions extending generally lengthwise of the device, means for rotating the device, means for actuating the members for advancing a thread carried in a generally helical path thereabout lengthwise of

the device, means for selectively putting the actuating means into and out of operation respectively, a frame member disposed adjacent one end of the device for supporting it, and a control member for the selective means comprising an arm pivotally connected to the frame at a point offset peripherally from the device and swingable into and out of a position extending alongside the device with the outer end of the arm engaging the outer end of the device to effect reversible interchange of operation of the device between a thread-advancing condition and a non-advancing condition respectively.

13. A thread-handling device comprising two sets of bar members, each set having their thread-supporting surfaces lying in a substantially cylindrical surface, means for rotating the device, means for actuating at least one set of bars relative to the other for effecting thread-advancing movement therealong, means for selectively putting the actuating means into and out of operation respectively, a frame member disposed adjacent one end of the device for supporting it, and a control member for the selective means comprising an arm carried by the frame member and movable to and from a position of engagement with the other end of the device to effect reversible interchange of operation of the device between a thread-advancing condition and a non-advancing condition respectively.

14. A thread-handling device comprising two sets of bar members, each set having their thread-supporting surfaces lying in a substantially cylindrical surface, means for rotating the device, means for actuating at least one set of bars relative to the other for effecting thread-advancing movement therealong, means for selectively putting the actuating means into and out of operation respectively, a frame member disposed adjacent one end of the device for supporting it, and a control member for the selective means projecting generally axially through the device to the unsupported end thereof.

15. A thread-handling device comprising two sets of bar members, each set having their thread-supporting surfaces lying in a substantially cylindrical surface, means for rotating the device, means for actuating at least one set of bars relative to the other for effecting thread-advancing movement therealong, means for selectively putting the actuating means into and out of operation respectively, a frame member disposed adjacent one end of the device for supporting it, and a control member for the selective means comprising an arm pivotally connected to the frame at a point offset peripherally from the device and swingable into and out of a position extending alongside the device with the outer end of the arm engaging the outer end of the device to effect reversible interchange of operation of the device between a thread-advancing condition and a non-advancing condition respectively.

16. A thread-handling device comprising two eccentrically disposed sets of thread-supporting bars, the bars of each set having their thread-supporting surfaces lying in a substantially cylindrical surface, the two sets being rotatable bodily as a unit on the axis of one of them, the other set being mounted rotatably on its own axis eccentric to that of the first set, means for rotating the two sets simultaneously, means for actuating the bars of the second set relative to those of the first set to advance the thread lengthwise

11

of the device, means for selectively putting the actuating means into and out of operation respectively, a frame member disposed adjacent one end of the device for supporting it, and a control member for the selective means comprising an arm carried by the frame member and movable to and from a position of engagement with the other end of the device to effect reversible interchange of operation of the device between a thread-advancing condition and a non-advancing condition respectively.

17. A thread-handling device comprising two eccentrically disposed sets of thread-supporting bars, the bars of each set having their thread-supporting surfaces lying in a substantially cylindrical surface, the two sets being rotatable bodily as a unit on the axis of one of them, the other set being mounted rotatably on its own axis eccentric to that of the first set, means for rotating the two sets simultaneously, means for actuating the bars of the second set relative to those of the first set to advance the thread lengthwise of the device, means for selectively putting the actuating means into and out of operation respectively, a frame member disposed adjacent one end of the device for supporting it, and a control member for the selective means projecting generally axially through the device to the unsupported end thereof. 25

18. A thread-handling device comprising two eccentrically disposed sets of thread-supporting bars, the bars of each set having their thread- 30

12

supporting surfaces lying in a substantially cylindrical surface, the two sets being rotatable bodily as a unit on the axis of one of them, the other set being mounted rotatably on its own axis eccentric to that of the first set, means for rotating the two sets simultaneously, means for actuating the bars of the second set relative to those of the first set to advance the thread lengthwise of the device, means for selectively putting the actuating means into and out of operation respectively, a frame member disposed adjacent one end of the device for supporting it, and a control member for the selective means comprising an arm pivotally connected to the frame at a point offset peripherally from the device and swingable into and out of a position extending alongside the device with the outer end of the arm engaging the outer end of the device to effect reversible interchange of operation of the device between a thread-advancing condition and a non-advancing condition respectively. 20
